[57] CLAIM

The ornamental design for long jump foot fault detector, as shown and described.

DESCRIPTION

FIG. 1 is a top perspective view of a long jump foot fault detector showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top perspective view of a second embodiment thereof;

FIG. 9 is a top plan view thereof, with the bottom being the same as shown in FIG. 3;

FIG. 10 is a rear elevational view thereof, with the front being the same as shown in FIG. 4; and,

FIG. 11 is a left side elevational view thereof, with the right side being the same as shown in FIG. 7, except for the omission of the light elements.

FIG. 1**FIG. 2****FIG. 3****FIG. 4****FIG. 5****FIG. 6****FIG. 7****FIG. 8****FIG. 9****FIG. 10****FIG. 11**
